TOY MONORAIL CAR

Robert G. Johnson, 22109 110th Ave. W., Edmonds, Wash., and Truxton B. Troxell, 108 N. 155th St., Seattle, Wash.

Filed Mar. 4, 1964, Ser. No. 78,872

Term of patent 7 years

(Cl. D34—15)

FIGURE 1 is a top perspective view of the toy monorail car, showing our new design;

FIGURE 2 is a side elevational view thereof;

FIGURE 3 is an end elevational view thereof;

FIGURE 4 is a top plan view of one end portion thereof.

The dominant features of our design reside in the full-line portions of the drawing.

A dominant feature of the design is the combination of a pulley-mounting pillar shell integrated with a circumferential rib at the open end of the cap which fits onto the end of a conventional tin can, the monorail car being composed of two identical caps fitted on the opposite ends of a tin can.

This application is a continuation-in-part of our patent application Serial No. D. 70,343, filed May 29, 1962, now abandoned, which application was a continuation-in-part

of our earlier patent application Serial No. D. 67,996, filed December 20, 1961, now abandoned.

We claim:

The ornamental design for a toy monorail car, substantially as shown and described.
